CAMERA CASE

Jay Doblin, Chicago, Ill., assignor to Whitehouse
Products, Inc., Brooklyn, N.Y., a corporation of
New York

Filed Aug. 27, 1965, Ser. No. 86,753

Term of patent 14 years

(Cl. D87—5)

FIG. 2.

FIG. 1.

FIG.4.

FIG.6.

FIG.3.

FIG.5.

FIG.7.

FIG.8.

FIG.9.

FIG.10.

FIG.11.

FIG. 1 is a front elevational view of a camera case embodying my design, the case being shown in latched position;

FIG. 2 is a rear elevational view of the camera case of FIG. 1;

FIG. 3 is a fragmentary front elevational view of the camera case of FIG. 1, the case being shown in unlatched position;

FIG. 4 is a top plan view of the camera case of FIG. 1;

FIG. 5 is a top plan view of the camera case of FIG. 1 with the carrying strap removed, the case being shown in latched position;

FIG. 6 is a top plan view of the camera case of FIG. 1 with the carrying strap removed, the case being shown in unlatched position;

FIG. 7 is a left side elevational view of the camera case of FIG. 1, the case being shown in latched position;

FIG. 8 is a right side elevational view of the camera case of FIG. 1, the case being shown in unlatched position;

FIG. 9 is a bottom plan view of the camera case of FIG. 1;

FIG. 10 is an elevational view of the inside of the camera case of FIG. 1 with the case opened; and

FIG. 11 is a side view of the camera case as shown in FIG. 10.

I claim:

The ornamental design for a camera case, as shown.
